ATTORNEY

WITNESS:

UNITED STATES PATENT OFFICE.

WILLIAM F. WINTERLING, OF CAMBRIDGE, MARYLAND, ASSIGNOR OF ONE-FIFTH TO WILLIAM GRASON WINTERBOTTOM, SR., ONE-FIFTH TO LEVI B. PHILLIPS, SR., ONE-FIFTH TO ALBANUS PHILLIPS, SR., AND ONE-FIFTH TO CHARLES L. JANNEY.

TIME SWITCH FOR PARKING LAMPS.

Application filed October 23, 1922. Serial No. 596,370.

This invention relates to an automatic switch for a parking lamp of a motor vehicle, the general object of the invention being to provide a time switch for closing the 5 circuit of the lamp at any desired time and breaking the circuit after the elapse of a predetermined period of time.

Another object of the invention is to associate the switch with a clock which may 10 be located on the dash of the instrument so that the device will also act as a time recorder as well as an automatic switch for the parking lamp.

This invention also consists in certain 15 other features of construction and in the combination and arrangement of the several parts, to be hereinafter fully described, illustrated in the accompanying drawings and specifically pointed out in the appended 20 claim.

In describing my invention in detail, reference will be had to the accompanying drawings wherein like characters denote like or corresponding parts throughout the several 25 views, and in which:

Figure 1 is a front view of the invention.

Figure 2 is a section on line 3—3 of Figure 1.

Figure 3 is a section on line 4—4 of Figure 2.

Figure 4 is a rear view of the time piece with parts broken away.

Figure 5 is a section on line 6—6 of Figure 5.

Figure 6 is a view of a modification.

Figure 7 is a cross section through the contact members.

In these views 1 indicates a casing which is preferably secured to the dash of the motor vehicle. Within this casing is located a pair of spring contacts 2 which are insulated from each other and which are arranged in the circuit of the parking lamp. A time piece 5 is carried by the casing it being detachably connected therewith by means of the hinged part 6 which is so arranged as to expose the face of the time piece so that the time can be read therefrom. This time piece has adjustably secured to its rear face 50 a spring strip 7 which carries a projection 8 of insulating material which projects through a hole 9 in the transparent rear

cover 10 of the time piece. The parts are so arranged that when the strip 7 is forced outwardly, by means hereinafter to be described, the projection 8 will engage one of the spring contacts 2 and press it against the other contact, thus closing the circuit to the parking lamp. The means for moving said strip 7 consists of a toothed wheel 11 which 55 is actuated from the minute hand arbor 12 through means of the disc 13 and pin 14 and which carries a cam 15 for engaging the pointed end of the strip 7 so as to raise the strip and then when the cam leaves the 60 pointed end the strip will return to its normal position and thus permit the contacts 2 to spring apart and break the circuit. As will be seen the wheel 11 is given a step by 65 step rotation and is moved one step upon 70 each revolution of the minute hand arbor.

The wheel 11 is rotatably mounted on a set screw 17 and its teeth are engaged by a spring pawl 18 which is adjustably held to the time piece by the screw and slot connection 19. A switch 20 is connected with the casing 1 so that the circuit can be broken at any desired time by pulling out the slide 21 and thus making a gap between the terminals 22 to which the conductors 23 are 80 connected.

From the foregoing it will be seen that the wheel 11 will be rotated from the minute hand arbor so that at a certain time the cam will be brought under the pointed end of 85 the strip 7 so as to force the projection 8 carried by the strip against one of the spring contacts 2 to press the same against the other contact, thus closing the circuit to the parking lamp to light the same. The circuit 90 will remain closed and the lamp lighted until the wheel has moved a sufficient distance to cause the cam to pass from under the strip when the strip will spring back to its normal position, thus permitting the contacts 2 to separate and thus break the circuit. The wheel 11 can be adjusted manually to bring the cam under the strip at any desired time and the adjustable pawl 18 not only acts to prevent the too free movement of the wheel but also acts as a means of making a fine adjustment of the wheel 95 so that the lights can be turned on between the hours.

In the modification shown in Figure 6 the cam 15' engages a spring arm 7' which acts to force an insulated contact button 26 on the spring blade 2' against a similar contact button on another blade and thus close the circuit to the parking lamp as before described. This spring arm 7' passes through a slot 24 in the rim of the cover 10' and said arm moves in a plane parallel to the rear face of the time piece. The cam 15' is of semi-circular shape and its curved edge engages the arm. The wheel 11' is engaged by a pinion 25 on the minute hand arbor of the time piece. By having the contact buttons 26 insulated from their blades there is no danger of magnetizing the watch mechanism. In other respects this form of the invention is similar to that above described.

It will be seen that this invention provides means whereby a motorist can cause a parking lamp to be lighted when it becomes dark enough to have a light and then the lamp will be extinguished the next morning if

it has not been extinguished before by means of the switch 20.

25

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A switch operating device comprising a 35 time piece, a spring member therein having a part projecting therefrom for engaging a switch, a toothed wheel in the time piece, a cam thereon for engaging the spring member to cause the same to actuate the switch 40 and means for giving the toothed wheel a step by step movement from the minute arbor of the time piece.

In testimony whereof I affix my signature.

WILLIAM F. WINTERLING.
